Primary Examiner — Janice Hallmark(74) *Attorney, Agent, or Firm* — McGarry Bair PC(57) **CLAIM**

The ornamental design for a ceiling fan motor housing, as shown and described.

DESCRIPTION

FIG. 1 is a top perspective view of a ceiling fan motor housing, shown in the environment of a ceiling fan, showing my new design.

FIG. 2 is a top perspective view thereof, having the ceiling fan environment removed;

FIG. 3 is a bottom perspective view thereof;

FIG. 4 is a top view thereof;

FIG. 5 is a bottom view thereof;

FIG. 6 is a front view thereof;

FIG. 7 is a rear view thereof;

FIG. 8 is a right-side view thereof; and,

FIG. 9 is a left-side view thereof.

Portions of the ceiling fan motor housing and ceiling fan environment shown in broken lines form no part of the claimed design. The unshaded surface areas located between solid lines and broken lines form no part of the claimed design.
